ROUGHING MACHINE

Erastus E. Winkley, Lynn, Mass., assignor to
 United Shoe Machinery Corporation, Borough
 of Flemington, N. J., a corporation of New
 Jersey

Application February 5, 1940, Serial No. 317,290

5 Claims. (Cl. 69—1)

This invention relates to roughing machines and will be described herein as embodied in a machine for roughening the overlasted margin of the upper of a lasted shoe in order to prepare it for the reception of cement. The invention, however, is not limited in all its aspects to embodiment in an upper roughing machine, certain features thereof being readily adaptable to roughing machines used for other purposes such, for example, as roughening outsoles or other shoe parts.

When roughening the overlasted margin of a shoe upper, it is desirable that a uniformly thin layer of material be removed from the surface of the work and experience has taught that this operation is most satisfactorily performed with a rotary tool such as a wire brush. Inasmuch as there are usually radial pleats and wrinkles in the overlasted margin of the upper, it is necessary, in order to insure treatment of all of the exposed surfaces, that the direction of action of the tool be transverse to the overlasted margin of the shoe upper, from the outer edge of the shoe bottom inward.

In order to avoid the formation of a substantial concavity or trough in the roughened band or stripe with a brush which rotates and cuts cross-wise of the band, it is customary to use a brush of rather large diameter since the greater the diameter of the brush the less the amount of convexity in its face in a segment of a given width. Large brushes are expensive and their accommodation in a machine sometimes imposes inconvenient limitations upon the machine design.

It is an object of the present invention to provide a compactly designed roughing machine in which can be used a rotary roughing tool of relatively small diameter, which tool, however, operates in a path that approaches a straight line as closely as would the operative face of a tool of a diameter so great as to exceed practical limits.

With the above stated object in view, a feature of the invention consists in the combination, with a rotary roughing tool and driving means for rotating said tool, of means for oscillating said tool bodily while it is rotating. In the illustrated machine, the tool is rotated at a substantially constant speed and is simultaneously oscillated bodily at a lower speed about an axis outside of the tool itself, the oscillatory movement of the tool being in the same direction as the movement of its periphery resulting from the continuous rotation about its own axis. This compound movement is preferably obtained by journaling the tool at the free end of a swinging arm of substantial length and continually oscillating the arm about a fixed pivot while the tool rotates. The result of this is that the cutting face of the

tool at the place where it acts upon the work moves in a nearly flat arc, the radius of which is the distance from the periphery of the tool to the pivot about which the arm oscillates, and this radius can have any desired magnitude within reason.

A further feature of the invention is to be recognized in the combination with the above described roughing tool of a shoe support positioned to sustain a lasted shoe with the overlasted margin of its upper disposed across the path of action of the tool. The shoe support preferably comprises a roll mounted below the level of the roughing tool with means for rotating the roll about a horizontal axis perpendicular to the axis of rotation of the tool and means for raising and lowering the roll at will to cause the shoe to be presented properly to the tool as the roughing operation progresses around the margin of the shoe bottom.

These and other advantageous features of the invention, including a novel structure for retaining the roughing tool upon its support but permitting its instantaneous removal therefrom, will be better understood and appreciated upon reading the following detailed description of a machine embodying the invention in connection with the accompanying drawings, in which.

Fig. 1 is a side elevation with parts of the housing removed to reveal the operating mechanism;

Fig. 2 is a front elevation;

Fig. 3 is a plan view of that part of the mechanism which imparts combined rotary and oscillatory movement to the roughing tool; and

Fig. 4 is a sectional view of the tool.

Referring to the drawings, 10 indicates a housing of which parts are removed to reveal the mechanism therein. Power is transmitted from a motor 12 by a belt 14 to the roughing tool rotating mechanism, and by a belt 16 to a pulley 18 affixed to a shaft 20 from which are derived the rotary motion of the work supporting roll and the oscillatory movement of the roughing tool.

The roughing tool, as illustrated, consists of a wire brush 22 rotatably sustained upon a stud 24 secured in the outer end of an arm 26, which is pivotally mounted upon a shaft 28, about the axis of which the arm can oscillate. Affixed to the shaft 28 is a pulley 30 around which the belt 14 passes and by which the shaft 28 is rotated. Also affixed to the shaft 28 is a pulley 32 connected by a belt 34 to a pulley 36 by which the roughing brush is rotated. Thus, when the motor 12 is running, the roughing brush will be rotated continuously by power transmitted through the belts 14, 34.

The mounting of the tool-carrying arm 26 comprises a sleeve 38 which is loose upon the shaft 28 and to which the arm 26 is secured. The arm,

as shown, is made in two sections connected together by bolts 40, passing through slots 42 in one of the sections, to provide for adjustment of the length of the arm in order to obtain the proper tension in the belt 34.

Projecting rearward from the sleeve 33 is an arm 44 having a longitudinal hole in which a rod 46 is slidable. The outer end of the rod 46 carries an eccentric strap 48 which surrounds an eccentric 50 fixed upon the shaft 28. When the motor 12 is running, this shaft 28 which is driven by the belt 16 also rotates continuously and, consequently, the eccentric 50 will cause continual oscillation of the sleeve 33 and up and down movement of the tool-supporting arm 26. The radius of the arc, in which the operative portion of the roughing brush 22 oscillates, is equal to the distance between the center of the shaft 28 and the point where the brush engages the shoe. It will be apparent from an inspection of Fig. 1 that the effect will be the same as if a brush rotating about a fixed axis and having that large a radius were being used.

In order to facilitate the proper presentation of the shoe to the roughing brush, a large, work supporting roll 52 is provided. This roll is carried by a shaft 54 journaled in a housing 56, the rear portion of which is formed to enclose a worm gear 58 secured to the shaft 54. The worm gear 58 meshes with a worm 60 fixed upon the shaft 20 and the housing 56 carries bearings which are supported by and freely rotatable upon the said shaft so that the housing, together with the worm gear 58 and the shaft 54 contained therein, can swing about the axis of the shaft 20. The purpose of this arrangement is to permit the roll 52 to be raised or lowered at will while the machine is running, in order that the shoe may be presented accurately to the roughing brush. The housing 56 is connected by a rod 62 to a treadle 64, which is normally elevated by a spring 66 to sustain the work-supporting roll 52 in the position shown in full lines in Fig. 1. By depressing the treadle, the roll may be lowered to the position indicated by dotted lines or to any intermediate position.

In order to predetermine the upper and lower limits of movement of the roll 52, upper and lower adjustable stops 68, 70 are provided. These stops are mounted in a slot 72 in a stationary guide 74 between which and a similar parallel stationary guide 76 a suitably formed portion 78 of the housing 56 is vertically movable.

The structure and mounting of the roughing brush 22 are best illustrated in Figs. 3 and 4. The active elements of the brush consist of the usual wire bristles arranged in the form of an annulus and secured in a ring 80 which is pushed upon a sleeve 82 having a flange 84 for confining the bristles at one side of the brush. A rubber washer 86 is pressed against the other side of the brush by a metallic washer 88 engaged by a nut 90 threaded upon the end of the sleeve 82.

The pulley 36 has a hollow hub 92 upon which the sleeve 82 has an easy, sliding fit, and a pin 94 projecting from the side of the pulley enters a hole in the flange 84 to prevent relative rotation of the brush and the pulley. The brush, although it is positively driven by the pulley 36, is entirely unsecured and can be instantly removed from the hub of the pulley without the use of tools.

In order to retain the roughing brush in operative position upon the pulley hub 92, there is provided, for closing an opening in the side of

the housing 10, a closure member 96 which is hinged to the rest of the housing at 98. An abutment disk 100 is adjustably secured in the closure member 96 and is arranged to engage the end 6 of the sleeve 82 when the member 96 is in closed position, as illustrated in Figs. 2 and 3, thus retaining the roughing tool and its pulley upon the stud 24. The upper hinge portion of the closure member 96 has a square corner 102 (Fig. 3) against one or the other of the two sides of which bears a spring pressed pin 104 serving to retain the closure member in either closed or open position but permitting said member to be moved instantly from one position to the other. 10 This construction permits the roughing tool to be removed for sharpening or replacement by merely opening the closure member 96 and picking the unsecured tool off its support.

In order to aid the operator in controlling the 20 presentation of the shoe to the roughing tool, there is provided a gage 106, the shank portion 108 of which is slidably mounted in a portion 110 of the housing 10 and threaded for the reception of an adjusting nut 112 by means of 25 which the position of the gage may be varied as desired. A set screw 114 serves to clamp the gage rigidly in adjusted position.

Having described my invention, what I claim as new and desire to secure by Letters Patent of the United States is:

1. In a shoe roughing machine, the combination of a rotary roughing tool, driving means for rotating said tool, means for oscillating said tool bodily in a plane at right angles to its axis of 30 rotation while it is rotating, and a shoe support so positioned relatively to the tool that a lasted shoe may be sustained upon said support with the overlasted margin of the shoe upper properly presented to the action of the roughing tool.

2. In a roughing machine, the combination of a rotary roughing tool, driving means for rotating said tool, a shoe support positioned to sustain a lasted shoe with the overlasted margin of its upper disposed across the path of action of the tool, 45 and means for oscillating the tool bodily across said overlasted margin.

3. In a shoe roughing machine, the combination of a rotary roughing tool, driving means for 50 rotating said tool about a horizontal axis, a shoe supporting roll mounted below the level of the roughing tool and offset horizontally from the axis thereof a distance approximately equal to the radius of the tool, and means for rotating said roll about a horizontal axis perpendicular to the axis 55 of rotation of the tool.

4. In a shoe roughing machine, the combination of a rotary roughing tool, driving means for 60 rotating said tool, a shoe supporting roll mounted below the level of the roughing tool and offset horizontally from the axis thereof a distance approximately equal to the radius of the tool, power means for rotating said roll about a horizontal axis, and means for raising and lowering said roll at will during operation of the tool and roll.

5. In a roughing machine, the combination of 65 a housing having an opening therein, a stud within the housing near said opening, a pulley having a hub rotatably sustained on the stud, an unsecured roughing tool sustained on said hub, and a movable closure member for said opening adapted to engage and retain the tool upon the hub when said member is in position to close the opening.

ERASTUS E. WINKLEY.
